UNITED STATES PATENT OFFICE.

JOSEPH L. FIRM, OF BERWYN, ILLINOIS, ASSIGNOR TO THE GOSS PRINTING PRESS COMPANY,
OF CHICAGO, ILLINOIS.

CUTTING AND FOLDING DEVICE FOR PRINTING-PRESSES.

No. 868,856.

Specification of Letters Patent.

Patented Oct. 22, 1907.

Application filed April 30, 1907. Serial No. 371,124.

To all whom it may concern:

Be it known that I, JOSEPH L. FIRM, a citizen of the United States, residing at Berwyn, in the county of Cook and State of Illinois, have invented certain new 5 and useful Improvements in Cutting and Folding Devices for Printing-Presses, of which the following is a specification.

This invention relates to transverse cutting and folding devices for cutting a plurality of longitudinal folded 10 webs, used in rotary perfecting printing presses.

Heretofore, single cutting blades have been used, but the capacity thereof is limited, with respect to the number of sheets they will cut, and hence they are objectionable or impossible of use where a large number of 15 webs are superposed and folded and delivered together.

In the present invention double cutting blades are used, located in opposite cylinders or carriers, and cutting toward each other, each of the cutting devices forming a matrix co-acting with the blades to cut the 20 top and bottom layers of a plurality of webs superposed upon each other. This is done with a single rotary carrier, in which the folding, cutting and delivery is all done at one operation.

The invention is illustrated in the accompanying 25 drawings, in which

Figure 1 is a diagrammatic section of a rotary transverse cutter and carrier provided with the invention. Fig. 2 is a similar view of a carrier having a double feed and delivery. Fig. 3 is a side view in detail, showing 30 the edges of the knives and the manner in which they coöperate. Fig. 4 is a detail in side elevation of one of the knife sections and the adjacent fiber block. Fig. 5 is a side view of the knife box, showing wedges to adjust the same in or out.

35 In the construction shown in the drawings, the body of the rotary carrier and the impaling pins and the folders may be of the usual construction, the pins and folders being controlled or operated by cams and levers in the ordinary manner, such as shown and described in 40 my U. S. Patent No. 658209, to which reference may be made for the details of construction.

The webs pass between the rotary cylindrical carrier A and the cutting cylinder B. Each of these cylinders has a longitudinal mortise cut in the body thereof and 45 extending from end to end, to receive the supporting boxes K which hold and support the cutting blades and the yielding fiber blocks. Each block has an inclined bottom with a wedge L thereunder which may be adjusted to set up the box as desired.

50 The opposite boxes have cutting blades 1 and 2 fixed therein, and on opposite sides of the blades are the fiber blocks 4, 5, 6 and 7, supported by springs 12, 13, 14 and

15 thereunder. The edges of the opposite blades are presented toward each other, with a slight lap or offset, which may be produced by greater bevel on one side 55 than on the other. The springs under the fiber blocks serve to clear the sheets from the knives as soon as the cut is made.

The cutting edges of the blades are toothed or serrated, as indicated in Fig. 3, the serrations being arranged, and the blades being adjusted, so that the teeth of one blade will be presented toward and work across the spaces between the teeth of the other blade, whereby the teeth will penetrate superposed webs from opposite sides and give the action and effect of a shear cut 65 which will effectively sever all the webs, and will cut through a much thicker body of material than a single straight-edged blade.

The springs under the opposite fiber blocks of the respective cylinders advance the same beyond the surface of the respective cylinders, so as to nip the webs therebetween, on both sides of the knives, which holds the webs taut, so that they are readily cut by the co-acting knives, the fiber blocks yielding to allow the webs to pass therebetween and also acting to clear the 75 webs from the knives after being cut.

The ends of the cutting cylinder and the carrier preferably have two segment gears D and E which engage with each other as the cutting action takes place. These gears are located adjacent the ends of the cutting 80 boxes and insure the exact registry or position of the cutting blades with respect to each other.

After being cut the impaling pins carry the sheets or papers around with the carrier and they are transversely folded off by the folding blades 18 which thrust 85 the same between the rollers 16 and 17, to any suitable delivery in the usual manner.

In Fig. 2 the carrier is shown provided with a double feed and delivery, as shown in my pending application Number 354101, the cutting devices of the carrier co-operating alternately with the cutting devices of the opposite cylinders B and C, the completed papers being delivered at opposite sides between the pairs of rollers 16 and 17, and 20 and 21, respectively.

I claim:

1. The combination of coöperating rotary cylinders, knives carried by the cylinders, the cutting edges of the knives being serrated and presented toward each other when cutting, with the teeth of one knife between the teeth of the other and coacting to cut webs or sheets 100 passed between the cylinders, and gripping blocks extending along beside the knives and having matrices therefor.

2. The combination of a rotary carrier cylinder, a cutter cylinder coöperating therewith, each cylinder having a knife carried thereby, and a yielding gripping block opposite the knife of the other cylinder, the cutting edges 105

of the knives being serrated and arranged to come together and slightly lap each other with the teeth of one knife between the teeth of the other as the cylinders are rotated, and to coact on webs or sheets passed between the cylinders.

5. 3. The combination of coöperating rotary cylinders, opposite coacting knives carried respectively by the cylinders, to cut webs or sheets passed therebetween, and yielding gripping blocks extending along beside the knives, the

blocks of the opposite cylinders each having a matrix 10 extending along beside the knife therein to receive the edge of the opposite knife.

In testimony whereof I affix my signature, in presence of two witnesses.

JOSEPH L. FIRM.
